Application February 19, 1938, Serial No. 191,513

26 Claims. (CL 250—11)

Our present invention is concerned with radiating systems for radio transmission. In particular, it is concerned with antennas that restrict the radiation largely to directions desired using comparatively short radiating conductors.

Directional antennas of various kinds are well known in this art. They are of such common use that some technical expressions applicable to them have been developed. We will use these expressions in setting forth both the objects of our invention and the methods for accomplishing it. Examples are: "half-wave antenna;" a single vertical grounded conductor one-half wave length high; "end-fire array;" a row of antennas in a line radiating largely in the direction of the line; "gain;" the ratio of power required by a vertical dipole antenna to that required by some other specified antenna to produce the same field strength at a specified distance in a specified direction from the antennas.

Probably the commonest form of antenna used for radiation at the ordinary broadcast frequencies where the energy is desired largely at low elevations, that is, as nearly as possible parallel to the ground, is a vertical conductor about a half wave length high. This type of radiator sends very little energy vertically above it and comparatively little at angles above 45° from the horizontal. Inasmuch as this kind of antenna is widely and satisfactorily used, we consider it as a convenient standard by which the performances of others can be judged. The vertical half-wave antenna has also been supplemented by an enclosing ring of shorter antennas, of the order of one-tenth wave length high which are intended to suppress radiation at high angles from the ground and thus to improve the vertical directivity of the antenna.

In addition to the vertical half-wave antenna, radiating arrays comprising a plurality of antennas of less than a half wave length high are also known. These arrays are usually in circular arrangements of vertical antennas. Arrays of one, two, or more concentric circles are known. These arrays are intended to accomplish directive radiation without the use of very high antennas. Our present invention is concerned with the improvement of the circular array type of radiating system and the extension of its capabilities.

The principal object of our invention is to accomplish vertical directivity with short antennas. Further, we have the object of getting more nearly the most desirable directional characteristics thus producing a desired field intensity at a specified distance with less power than is required by

other systems. Another object is to produce antennas with desired directional characteristics in the horizontal plane in various patterns as well as with vertical directional characteristics.

For the disclosure of our invention we use the following figures:

Figure 1a, a ground plan of a multiple ring polyphase radiating system.

Figure 1b, a plan of a second multiple ring polyphase radiating system.

Figure 1c, a plan of a combination of the systems shown in Figures 1a and 1b showing the horizontal field pattern of the resultant system.

Figure 2a, a ground plan of a single ring radiating system with vertical directivity.

Figure 2b, a vector diagram pertaining to Figure 1a.

Figure 2c, a polar diagram comparing the vertical directivity of the system shown in Figure 2a with that of a vertical dipole and a vertical antenna one-half wave length high.

Figure 3, a ground plan of a multiple ring radiating system having vertical directivity.

Figure 4, a ground plan of a second form of multiple ring radiating system having both vertical and horizontal directivity.

Figure 5a, a vector diagram of a form of single ring radiating system having both vertical and horizontal directivity.

Figure 5b, a ground plan pertaining to Figure 3a.

Figure 6a, a vector diagram of a second form of single ring radiating system having both vertical and horizontal directivity.

Figure 6b, a ground plan pertaining to Figure 3a.

In accomplishing the objectives of our present invention, radiating arrays are produced which restrict the radiation largely to angles near the horizon, in horizontal patterns which may be circular or of a number of other useful patterns, such as a figure eight distribution. We will show three methods of treating the problem. The first method considers ring-shaped arrays as combinations of a plurality of end-fire arrays excited with polyphase currents. The second treats a single ring array from a novel vectorial point of view for qualitative explanation. The third method treats the combinations of end-fire arrays and the single ring array mathematically for rigorous computation, and it produces formulated results applicable to complex combinations of multiple ring antennas with any desired combination of phases in excitation.

We refer first to Figure 1a which shows a three- 55

phase radiating system. In the system there are three intersecting end-fire arrays marked A—A', B—B', and C—C'. Each array is composed of seven vertical antennas in a line. Those in array 5 A—A' are numbered from 1 to 7 inclusive. They are spaced a distance of the order of one-half wave length apart for purposes of explanation, but, as we will show later, the optimum spacing is usually different from half a wave length. The 10 antennas may be of any convenient height from about an eighth of a wave length or less to half a wave length or more. The radiation pattern for an end-fire array, once the antenna locations, dimensions, and connections are known, can be 15 calculated by methods known in the prior art. For example, it may approximate the figure 8 shape shown by the line drawn concentric with the array A—A'. At the ends there are two large lobes representing a horizontal plan of field 20 strength at the ground level in which the length of a line drawn from the center to the figure 8 line is proportional to field strength at the array in the direction under consideration. At the center there are some small lobes or "ears" representing 25 radiation in directions transverse to the axis of the array. The relative polarities of the individual antennas are indicated by + or - signs in the circles. If a + indicates at the instant of observation current flowing from the 30 top of the antenna toward the ground, the - would indicate current flowing from the ground toward the top. The antenna polarity alternates from one antenna to the next progressing radially. Each of the three arrays are identical in 35 structure and general character and have the same form of radiation pattern.

The radiating system of Figure 1a is made by combining the three antennas and exciting them by currents differing in phase by 120 electrical 40 degrees in progressing around the circumference from one array to the next. That is, the currents in A—A' would be 120° ahead, for example, of the currents in B—B' and those in B—B' would lead the currents in C—C' by 120°. In 45 the arrangement of the antennas on the ground we show them intersecting at a point common to the centers of all the arrays so the total array appears as a group of concentric rings. This is a convenient and desirable arrangement but it is not necessary. The individual antennas in the 50 several end-fire arrays can be in other than straight lines and the arrays can be arranged intersecting at any desired angle or can be spaced apart so they do not intersect at all. However, 55 the convenience, especially for computation of the design, of the concentric circular arrangement makes it the preferred one. Accordingly we will discuss the system for convenience in terms of the concentric ring arrangement. Looking 60 at any one of the rings of antennas, the two antennas of each of the three phases, for example antennas 1 and 7, may be thought of as being analogous to two coil sides of each of the three phases of a three-phase, four-pole rotating armature field. The central antenna 4 being common to three phases 120° apart would carry no current so it could be omitted. The combination of the three intersecting antennas produces an array in which the array elements carry currents 65 differing in adjacent elements in such a way that in progressing along any radius, the phase difference between currents in adjacent elements is 180°, and in progressing around any ring, the phase difference between currents in 70 adjacent elements is constant and such that the 75

phase differences in progressing once around the array add to $2 \times 360^\circ$.

The horizontal resultant radiation pattern of the three-phase system at the ground level is roughly circular in shape. The radiation is concentrated largely in a relatively small angle near the horizon somewhat like the radiation of a vertical half-wave radiator but in general with greater concentration at the angles near the horizon. 10

In Figure 1a we have shown a symmetrical circular arrangement of the antennas but precise symmetry is not necessary for satisfactory operation. Neither is it necessary for the rows of antennas to be on straight lines, although this 15 has the advantage of permitting the use of a cable stretched along the line of an array and using the cable to support vertical conductors instead of using a tower at each place an antenna is required. Also the angle between the 20 arrays which for symmetry is 60° may be varied as desired to change the shape of the radiation pattern. The three-phase antenna suggests at once a two-phase arrangement where it is desired to use fewer antenna connections. A two-phase system can have two arrays intersecting 25 at right angles in which case there is a phase advance of 180 electrical degrees in each angular rotation of 90 mechanical degrees, or, for example, with four arrays rotating in phase 90 30 electrical degrees for each forty-five mechanical degrees of rotation or any other convenient combination of phases with angular rotation.

In Figure 1a the phase of the antenna currents advances 120 electrical degrees in each 35 mechanical degrees of rotation around the circle. Thus the polarity of the antenna 7 at A', 180° from A, is the same as that of antenna 1 at A. In this arrangement the polarity of the antennas alternates from 1 to 7 so that the polarities on 40 each side of the center antenna are images of those on the other side, that is, the polarities of antennas 3 and 5 are the same, 2 and 6 the same, and so forth. This condition will always be fulfilled where there is a whole number of 45 complete phase rotations in half the circumference of the ring, but if there is, for example, 1½ complete phase rotations in half the circumference, the antennas at opposite ends of the diameters will have opposite polarity. There 50 is nothing that requires an even number of phase rotations in one circumference. In fact, arrays having an odd number of rotations are to be desired in some circumstances.

In Figure 1b we show a radiating system having 55 three complete rotations of phase in one circumference of the ring. Starting from A the phase advances 120° to B and so on around the ring so that in half the circumference the phase advances $360 + 120 + 60 = 180$ electrical degrees. 60 To illustrate this we have numbered the real antennas at A as 11 to 14 inclusive. We have in Figure 1b antennas on 9 radii. We could have them on 18 radii in which case antennas 15 to 18 would be real antennas but this is more 65 antennas than is actually needed in a system of this kind. However, the complete end-fire array 11 to 18 exists in effect because the fields of the array sections marked B' and C' combine to produce a field which is the substantial equivalent of that which would be produced by antennas 15 to 18 if they were present. 70

The principal point to notice in this arrangement is that the polarities of antennas at opposite ends of a diameter are not the same and 75

that instead of placing the end-fire array so one of its antennas is at the center of the system, it is placed so the center is between two antennas of opposite phase. This puts the nine central antennas 14 and 19 to 25 inclusive close together near the center. Any three adjacent antennas in the inner ring, being excited 120° apart in phase have currents which add to zero, and being close together the radiation from the group of three is practically zero. Accordingly the inner ring of antennas may be omitted. They are shown dotted to emphasize this. Our precise computations, yet to be described, show that the performance of this particular arrangement is improved by omitting the inner ring, and still further improved if the ring is left but reversed in polarity at each antenna. These results are not apparent from qualitative considerations.

The arrangement shown in Figure 1b has an approximately circular horizontal radiation pattern, and high vertical directivity. In order to get horizontal field patterns of forms other than circular we combine polyphase systems having different numbers of phase rotations per circumference. For example, in Figure 1c we have combined the system shown in Figure 1a with that shown in Figure 1b. The circles in Figure 1c represent the antennas shown in Figure 1b and the squares represent the antennas shown in Figure 1a. The horizontal field pattern is indicated by the heart-shaped line Figure 1c. It is expressed mathematically as being proportional to the absolute value of the cosine of half the horizontal angle measured from a specified radius of the system. It will be noticed that several antennas are close together in pairs in Figure 1c and the logical procedure of combining them in single antennas in which the magnitude and phase of the current are made to serve for both antennas suggests itself. This is best accomplished by redesigning the entire system in accordance with the precise methods we will describe. The angle between the axis of symmetry of the antenna array and the axis of symmetry of the radiation field pattern can be varied at will by adjusting the phase relationship between the currents exciting the antennas represented by squares and those exciting the antennas represented by circles. In regard to computations it may be remarked that in general once having described a group of antennas with specified locations, and current magnitudes and phases, the radiation field pattern can be computed by methods known in the prior art, but the known methods do not, in general make it possible to derive a group of antennas together with their current magnitudes and phases that will produce a prescribed field pattern. We have invented methods for doing this which are set forth later in this specification.

We have now shown qualitatively how to get radiating systems having high vertical directivity by considering the systems as combinations of end-fire arrays. Before proceeding to the refinements of computation applicable to these systems we will show how directivity can be accomplished by a single ring of antennas. Later the general system will be developed as a combination of a plurality of ring arrays.

In Figure 2a we show an array of antennas distributed on the circumference of a circle. We will begin the discussion of Figure 2a by first considering how one might be led to a possible design of antenna. We will assume that the antenna is to radiate equally in all horizontal directions. That is, we desire an array with no obvious pre-

fferred direction. Perhaps the best form for an initial assumption is a circle. Let us therefore see what can be done with a continuous distribution of vertical dipoles arranged in a circular ring. Since there is to be no preferred direction the current in all antennas must be the same, though this is not necessarily true of the phases. A suitable current distribution, satisfying these requirements, is to have the dipole strength vary as $e^{in\phi}$ where ϕ is the azimuth angle measured from some arbitrary zero and n is as yet undetermined except that it must be an integer. As to the radius of our ring of antennas we may safely guess that if we are to get a considerable degree of vertical directivity the ring must be a wavelength or so in diameter. Thus, by purely qualitative arguments we can develop an antenna array that is likely to have the desired characteristics. A diagram of such an antenna is given in Figure 2a.

For computing the field that this array will produce at a large distance we can use a method used in the treatment of diffraction problems. This proceeds as follows. We consider ourselves to be at an observation point so far from the antenna that the distance to all parts of the array may be considered constant when figuring amplitudes, though not, of course, when figuring phases. Then the field due to any given element of the array may be represented by a vector of magnitude determined by the current in the element and of direction and phase dependent on the phase of the current in the antenna and the distance from the element to the observation point. The fields due to all the elements can be represented in the same way and the addition necessary to get the resultant field due to the addition of the individual components can be done by putting the various vectors end to end and so finding the vector sum.

Let us apply this to the antenna shown in Figure 2a. Before doing this we must actually select a value of n and also we must select a definite radius. Suppose we arbitrarily take $n=6$. As for the radius r , suppose we take a value such that, viewed from a distant point on the right, the phases of the elements near the top of the ring, for example antennas 0 and 11, appear to be constant. Under this condition the difference in the distances of the two antennas is just compensated by the difference in phase so the radiations from the two antennas arrive at the observer in phase. This makes $r=.9562\lambda$. Finally, for convenience in computation, let us replace our continuous ring of dipoles by 18 uniformly spaced dipoles numbered from 0 to 17 in Figure 2a. The vector addition produces the vector diagram shown in Figure 2b. In the straight section of Figure 2b as we go from element to element along the top of the ring the change in distance is exactly compensated by the changing phase of the antenna currents. As we go around the ring however the compensation gets less and less complete and finally, near the bottom of the ring, the vector diagram curls up completely. Roughly speaking the top of the ring acts like an end-fire array, and the effects due to the bottom elements practically cancel. The resultant radiation is represented by the distance between the two ends of the vector representing the vector sum of the components. Note that the vector in Figure 2b representing the radiation contribution of antenna number 9 in Figure 2a has been divided into two parts to make the vector diagram symmetrical. All this is when the

antenna is viewed from a point distant to the right in Figure 2b. If the observation point is in some other direction the vector diagram looks the same except that it is bodily rotated. Thus, it is evident that such an array will radiate equally well in all horizontal directions. Next it is found that it will also tend to confine the radiation to a horizontal plane by observing that, at angles above the horizontal, the compensation of changes of phase by different distances and different current phase can never be complete and so we can never get a straight section in the vector diagram. This is because, if the observer is above the horizontal, all the differences in distance from the observer to the various array elements are reduced so that differences in phase of radiation from the various array elements are apparent to the observer with the result that the resultant intensity of radiation is reduced. This follows from the condition that the change in current phase between adjacent array elements is just compensated by the difference in distance between adjacent elements in the horizontal plane so the observer on the horizontal receives maximum resultant radiation. When the observer is on the horizontal the difference between the several distances from the observer to the array elements is the same as the distances between the corresponding array elements, but when the observer is above the horizontal, the differences between the several distances from the observer to the array elements is less than the distances between the array elements, and it is no longer sufficient to compensate for the differences in current phase between the array elements. At the zenith the differences between the several observer-array distances are nearly zero and the vertical radiation is zero. For intermediate observing positions the successive vectors in the straightest part of a diagram like Fig. 2b will be at an angle to each other and the corresponding radiation less than represented by the diagram in Fig. 2b for the observer on the horizontal. Thus, in Figure 2b the center section of the vector diagram would become concave upward and the distance between ends, which determines the intensity, would be greatly reduced. In fact, it will be found that, for angles much above the horizontal, the intensity is very much reduced. So we see that it is possible to accomplish the desired object of vertical directional radiation using a ring of radiating elements.

Figure 2c shows a graph of the vertical radiation pattern of the array represented by Figure 2a. The line marked "array of Figure 2a" represents at any angle θ the field strength as the length of an arrow drawn from the origin out to the line. For comparison the radiation patterns of a half-wave antenna marked $\lambda/2$ and a dipole are also shown. It will be seen that the line representing Figure 2a is below that of the half-wave antenna down to angles of θ —about 80 degrees where they cross. This means that the array of Figure 2a concentrates its radiation more at angles near the ground than the half-wave antenna. The single ring of antennas presents a pattern of radiation in vertical planes through its origin that has no "ears" or "loops" of radiation pattern at angles near the vertical. All radiation is confined as indicated by the diagram 2c.

We have now shown qualitatively two ways of arriving at practical radiating systems having the desired directional characteristics. The methods of computation suggested by our qualitative analysis could of course ultimately be used for

purposes of design. However, the great number of variations possible in the dimensions of the arrays, number of rings, number of antennas in each ring, the number of phase rotations in each ring, the magnitudes of the currents, and other variable factors including departures from symmetry and height of antennas make the solution of the problems by the use of mathematical procedure derivable from the prior art too complicated and inaccurate to be fully satisfactory. Therefore, we have searched for a mathematical procedure which can simply and naturally add the effects of all the currents in an array taking into account phases and any other needed factors. Fortunately, it has been possible to develop such a calculational scheme and this has been described in a form suitable for the present purpose. From this point on, we will use this method entirely, and will not attempt any physical interpretation of the results. Using this method, we now try to find general radiating systems that will confine the radiation to angles near the horizon and will give any desired directivity in azimuth. This is a more general requirement than the one which we have used for our preliminary explanation.

We refer to Physics, vol. 7, No. 12, December 1936, page 460, W. W. Hansen and the references cited therein. We start with a slight modification of Equation 12 in the reference cited. Equation 12 follows:

$$E \approx \frac{+k^3 e^{ikr}}{2c kr} \sum (k\theta i^{-(n+1)} g_3(\theta) \sin \theta e^{in\phi} + k\phi i^{-n} g_2(\theta) \sin \theta e^{in\phi})$$

This equation shows that, at large distances the field can be expressed as what is essentially a Fourier series. Moreover if, as we shall assume for simplicity, the ground conductivity is good we find that only a vertically polarized component is present. This is given by

$$(1) \quad E_\theta = \frac{k^3 e^{ikr}}{c kr} \sum i^{-(n+1)} f_{3,n}(\theta) \sin \theta e^{in\phi}$$

where

$$(2) \quad f_{3,n}(\theta) = \frac{1}{2\pi k^2 \sin^2 \theta} \int \mathbf{i} \cdot \mathbf{A}_{3n} dt$$

and the A_{3n} are functions defined in the paper cited. Here r is the radius, θ is the vertical angle and ϕ the horizontal angle in spherical polar coordinates with the origin at the surface of the earth and the polar axis vertical.

To control the radiation pattern in the desired manner we have to show that it is in our power to control two things. First, we must be able to make the various $f_{3,n}(\theta)$ take on any desired value at $\theta = \pi/2$ in order to control the azimuthal distribution, and second we must be able to make the $f_{3,n}(\theta)$ drop off rapidly with departure from $\theta = \pi/2$ in order to confine the radiation to angles near the horizon.

To find out about $f_{3,n}$ we first examine $A_{3,n}$. We note that a considerable simplification will take place if we take i such that it has a z component vertical, that is, we let all the antennas be vertical or nearly so. Since this would be the normal thing to do in practice we adopt this simplification and thus insure that we need consider only the z component of $A_{3,n}$.

Next we observe that the z component of $A_{3,n}$ contains a term in $e^{ik \cos \theta}$. We note that this term can never deviate greatly from unity unless the antenna is a quarter wave or more high. Since an object of our present invention is to

5 avoid high antennas we simplify by approximating this term by one. If this approximation should not be good enough the exact calculation can be done and will in general indicate a slightly higher gain.

Making use of these simplifications we now write down a detailed expression for $f_{3,n}$, taking the needed definition of $A_{3,n}$ from the paper cited. We find

$$10 (3) \quad f_{3,n}(\theta) = \frac{1}{2\pi k} \int i_z J_n(k\rho \sin \theta) e^{-in\phi} d\tau$$

where J_n is a Bessel function, $k=2n/\gamma$, i_z the current density in the z direction, ρ and ϕ are the cylindrical coordinate radius and angle, and the integration is over the volume occupied by the antenna. We see that if i_z varies as some function of ρ times $e^{in\phi}$ then $f_{3,n}$ will be zero unless $n=n'$. Thus we see how to make any undesired $f_{3,n}$ vanish.

There remains the question of how to make $f_{3,n}$ decrease with departure from the angle $\theta=\pi/2$. In considering this problem we note that J_n is an oscillatory function. Thus, if we should take $i_z=\text{const.} \times e^{in\phi} J_n(k'\rho)$ out to some large radius, determined by the area available for the array, beyond which it is zero, and let $k'=k$ then we would find that for $\theta=\pi/2$, $\sin \theta=1$ and the integrand in (3) would be just J^2 , that is, always positive and for this angle the integral would be considerable. But at some other angle we would have $\sin \theta \neq 1$ and $J_n(k\rho)$ and $J_n(k\rho \sin \theta)$ would not stay in phase and approximately complete cancellation will occur with the result that $f_{3,n}$ will fall off for angles away from $\theta=\pi/2$, that is, the radiation will decrease at angles away from the horizontal. In regard to the mathematical interpretation of the quantities discussed above, it should be noticed that while values of θ can be found for which $J_n(k\rho \sin \theta)$ is greater than $J_n(k\rho)$, neither of these quantities determine $f_{3,n}(\theta)$ on which the intensity depends. Rather, it is the integral of their product over the volume of the antenna which determines $f_{3,n}(\theta)$. Of this volume integration, the integration over ρ and the height give only constants that are not of interest. The remaining integral over ρ is the determining one and it involves the product $J_n(k \sin \theta) J_n(k\rho)$ integrated from $\rho=0$ out to the radius of the array. To get this integral, which determines $f_{3,n}(\theta)$ and to have the intensity large, the integrand must be large and usually of the same sign, for example, when $\sin \theta=1$, we have

$$55 \quad \rho J^2$$

which is always positive. On the other hand if $\sin \theta$ is less than 1 then we have to integrate something much like the product of $\sin x$ and $\sin .7x$, for example, and the result will be small, perhaps even zero.

It can be verified analytically that the above analysis is in general a correct one. What is perhaps not so clearly evident is the observation that it is often profitable to make k' slightly larger than k . The results of doing this are two: first, the maximum value of $f_{3,n}$ is somewhat decreased because even at $\theta=\pi/2$ i_z and J_n do not stay in step, and second $f_{3,n}$ falls off more rapidly as θ departs from $\pi/2$. The first effect results in a slight lowering of the radiation resistance which is often not objectionable. The more rapid decrease of f however is quite marked and often increases the possible gain considerably, that is it assists in restricting the radiation to angles near the horizontal. Just how much k and k' should

differ depends on the diameter of the array and other things and is really a matter for individual consideration in each antenna design. Very roughly, however, the largest useful difference is that which makes $k' \rho_0$ and $k \rho_0$ differ by about 1.8 where ρ_0 =maximum radius of antenna. The same observation is applicable to straight line end-fire arrays. If ρ_0 is replaced by z_0 , the half-length of the array, a difference between $k' z_0$ and $k z_0$ of 1.47 for example increases the gain by a factor 1.81. This improvement can be effected in any existing end-fire array by readjusting the phases of the currents in the antennas. For example, in Figure 1a, considering only the single array of antennas 1 to 7 inclusive, the interval between successive antennas can be reduced from a half-wave length to a third-wave length and the phase difference between successive antennas changed from 180° to 120° . Then the radiation is confined to one direction, and one of the figure eight lobes shrinks almost to zero. This arrangement corresponds to known practice. By changing the phase difference between successive antennas from 120° to 148° as desired in our invention the directional gain is increased by a factor 1.81 mentioned before.

There is a special case under the general scheme of controlling $f_{3,n}$ that deserves particular mention. Namely, in case n is 1 or more, and especially when n is greater than 1, it is possible to have i finite for values of $k\rho$ less than that corresponding to the first maximum of J_n and zero for larger values than k . Then a decrease of $\sin \theta$ away from unity gives a rapid falling off in $f_{3,n}$. This is applicable to the single ring antenna. Figure 1 is a case of this when $n=6$ and the ring of antennas is put where $k\rho=6$ and the maximum value of J_6 is at about 8.

We are now ready to consider the actual design of a few typical arrays though it may be well first to note that it is possible for two arrays to give quite different fields and yet give the same directional pattern. This does not seem to be well known so we illustrate with a simple example. Suppose we want an antenna that gives uniform horizontal coverage. We can get this equally well with a field that is independent of ϕ or, for instance, with a field that varies like $e^{in\phi}$. In the first case the field is in phase at all values of ϕ whereas in the second the phase varies with ϕ . As will be shown presently the corresponding arrays are quite different but the absolute magnitude of the field at a large distance is the same.

We pass now to various examples illustrating the application of the above ideas to specific cases. First, suppose we want an antenna that distributes the radiation uniformly in azimuth but keeps it near the horizon. There are many ways of doing this but we will explain two that are more or less limiting cases.

For the first of these, let us try to get the field independent of ϕ , that is, $f_{3,0} \neq 0$, all other $f_{3,n}$ substantially zero. From the preceding discussion we see that if we had a continuous distribution of current of strength proportional to $J_0(k'\rho)$ up to some limiting radius ρ_0 and zero outside, then all $f_{3,n}$ except $f_{3,0}$ will be zero, and this will be large only for angles near the horizon. Moreover, it is plain that as to the variation with θ , the larger ρ_0 the better and in fact by making ρ_0 sufficiently large we can confine the radiation to angles as near the horizon as we choose.

Of course, the practical realization of such an array will not have the continuous distribution mentioned above but will have a finite number of

array elements so arranged as to give a sufficient 5
ly good approximation to the continuous distribution. Just exactly how this is to be done is
really a matter for detailed calculation in any
given case but the following rules can be laid
down. First, the antennas should be placed in
concentric rings. One ring for each maximum
or minimum of J_0 will be sufficient. The number
of elements in each ring depends on how much
10 variation of field strength with azimuth is al-
lowed but in general the number of antennas in
any given ring should be somewhat larger than
the $k\rho$ value corresponding to that ring.

As an example, we have drawn Figure 3, which
15 shows the location of array elements in such an
antenna. The antennas are represented by small
circles containing either a + or a -. These
signs indicate the phases of the currents in the
successive rings of antennas, which are 180°
20 apart. The currents in all the antennas of each
ring are in phase. This antenna uses 22 elements
inside a circle of radius 1.39λ . If the intensity
25 in the horizontal plane be considered as a function
of the azimuth angle, and if this function
be expanded in a Fourier's series in multiples of
the azimuth angle, the coefficients for amplitude
30 are, in order, 1.00, 0, 0, 0.17, 0, 0, 0.19, 0, 0, 0.17,
et cetera. That is, if ϕ is the azimuth angle, the
intensity will be $1+0 \cos \phi+0 \cos 2\phi+0 \cos$
 $3\phi+0.17 \cos 4\phi+0 \cos 5\phi+0 \cos 6\phi+0.19 \cos$
 $7\phi\dots$. Now, if all the cosine terms had zero
35 coefficients, we would have complete uniformity
of intensity in azimuth, and inasmuch as none
of the coefficients after the first are large, and
many are zero, it is evident that the field will be
almost circularly uniform in horizontal distribu-
40 tion. How effective the array is in confining the
radiation to angles near the horizon is perhaps
best stated by giving the gain, which is the ratio
of the power required by a vertical dipole to the
power required by the array in question when both
45 are giving the same signal on the horizon. In
the present example the gain is 2.31. This gain
can be increased by adding more rings. In this
connection the following approximate formula
is of value. If m is the number of rings the gain
50 is approximately given by

$$(4) \quad \text{gain} = 1.17\sqrt{m-1/2}$$

and the approximation gets better as m increases.
50 We now examine another way of keeping the
radiation near the horizon and keeping the dis-
tribution uniform in azimuth. This time let us
make $f_{3,6}$ finite and all other $f_{3,n}$ substantially
55 zero. This we can do by making the current vary
like $e^{i6\phi}$. Moreover, let us get the desired θ de-
pendence of $f_{3,6}$ by confining all the current to a
ring somewhere inside the first maximum of J_6 .
Just how far inside is a matter for individual de-
60 sign. To give an idea of what can be done we
may note that if the ring is put very near the
origin the gain comes out to be 2.06. The general
approximate formula for a case of this type is

$$(5) \quad \text{gain} = .752\sqrt{n+3/2}$$

65 where n is the order of the Bessel function used,
in this case 6. We may also note that putting
the array elements in a small ring results in very
small radiation resistance so that in practice one
would generally have the ring well out toward the
70 first maximum of the Bessel function. Such a
location greatly increases the radiation resistance
without serious loss of gain.

Finally we may ask how the continuous dis-
tribution is to be approximated by an actual ar-
ray. Here again more must be known of the in-

dividual requirements of a given case but in
general the minimum number of antennas in the
ring will be of the order of $2n+3$. Figure 2a is
an array of this type where $n=6$ and the ring is
at radius $k\rho=6$. Although 18 antennas are shown
5 in Figure 2, the number could be reduced to 15
without seriously reducing the uniformity of the
horizontal pattern of radiation. Mathematically
this question is best examined by expanding in
Fourier series. Such an expansion shows that a
10 ring of l array elements can be considered as a
superposition of an infinite number of continuous
ring distributions. As far as the angle depend-
ence goes, the expression

$$\dots e^{i(n-2)\phi} + e^{i(n-1)\phi} + e^{in} + e^{i(n+1)\phi} + e^{i(n+2)\phi} \dots \quad 15$$

is correct. We want the conditions so that such a
current distribution when inserted in Equa-
tion 3 will give substantially only one f , namely
15 f_{3n} . The only way this can be done is to make
 $J_{|n-2|}(k\rho)$, $J_{|n-1|}(k\rho)$ etcetera negligible in com-
parison with $J_n(k\rho)$ where ρ is the radius of the
ring. The crucial term is that with $J_{|n-1|}$. If
we make l equal to $2n$ we get $J_{|n-1|}=J_n$. By tak-
ing l larger one can increase the order of the
20 Bessel function $J_{|n-1|}$ and since, by hypothesis,
 $k\rho$ is inside the first maximum of J_n , increasing
the order will decrease the functions. Just how
much l must exceed $2n$ is not obvious, but inspec-
25 tion of the tables of functions shows that an ex-
cess of 3 will usually be sufficient.

Before leaving the subject of arrays that have
uniform horizontal coverage and which keep the
radiation confined to angles near the horizon
we want to mention explicitly that the multiple
30 ring J_0 antenna and the single ring J_n antennas
discussed above are not the only types that work
well. As a particular example we may refer to
the three-phase array shown in Figure 1a. In
the three-phase array, the current distribution
35 approximates $J_2 e^{i2\phi}$. The rings of antennas are
placed at radii corresponding approximately to
the first three maxima and minima of J_2 . The
currents in the rings of antennas differ in phase
40 by 180° from one ring to the next, and in all the
rings the currents vary in phase around the
rings as $e^{i2\phi}$, that is, the phase advancing from
45 antenna to antenna around the ring with two
complete phase rotations in one circumference of
the rings. In this example it will be noted in
particular that the rings of antennas are not
50 precisely at the radii corresponding to the max-
ima and minima of the Bessel function, as can
be verified by scaling the drawing and by refer-
ence to the published tables. This departure
55 from the optimum mathematical representation
can be made without materially decreasing the
effectiveness of the arrangement. Also the an-
tennas need not be in exact circles if the ground
situation prevents it although a circular place-
60 ment is preferred. Similarly the array shown in
Figure 1b has a current distribution approximat-
ing $J_3 e^{i3\phi}$, and the array shown in Figure 1c com-
bines the two arrays, one with currents of the
65 type $J_2 e^{i2\phi}$ and $J_3 e^{i3\phi}$.

As a second type of azimuthal pattern to be
achieved let us take the one in which the absolute
value of the electric field is proportional to
70 $|\cos \phi|$. Here, as before, there are many ways of
achieving the desired result, of which we illus-
trate only two.

For the first, let us take E as actually propor-
tional to $\cos \phi$, the absolute value signs being
omitted. This means $f_{3,1}=f_{3,-1}$, all other $f_{3,n}$ zero.
It can be verified that the desired current dis-
tribution will be proportional to $J_1(k\rho) \cos \phi$.
75

Here again the question of how many array elements will be needed arises, and, also as usual, we really need to know more details of the proposed installation. However, we have illustrated 5 a more or less typical array of this type in Fig. 4. In Fig. 4 there are three rings of antennas placed at radii prescribed by the first three maxima and minima of J_1 . Each antenna is represented by a small circle containing a + or a -. The currents from ring to ring going out along 10 a radius differ in phase by 180° . In each ring there is a variation of current proportional to $\cos \phi$ progressing from antenna to antenna around the rings.

15 The same result can also be obtained in other ways. For example, we note that if the field at large distances is proportional to $e^{in\phi} \cos \phi$ the absolute value of the field strength varies in the desired manner, that is, like $|\cos \phi|$. But

$$e^{in\phi} \cos \phi = \frac{e^{i(n+1)\phi} + e^{i(n-1)\phi}}{2}$$

Thus we get the desired result by having $f_{3,n+1} = -f_{3,n-1}$, all other $f_{3,n}$ zero. If n is larger 25 than one we can get the desired decrease of the f with θ by using a single ring of antennas and we will work out such a case to illustrate the use of the single ring antenna in applications like the present one. To be specific, suppose we take 30 $n=6$, as before, and agree to put a single ring of antennas at $k_p=6$. Then to get $f_{3,7}$ we need current density varying like $e^{i7\phi}$ going around the ring and to get $f_{3,5}$ we need a variation like $e^{i5\phi}$. The only point that might be overlooked 35 is that the part that varies like $e^{i7\phi}$ must be relatively stronger than that varying like $e^{i5\phi}$ since $J_7(6) < J_5(6)$. Thus the current around the ring should vary as $J_7(6) e^{i5\phi} - J_5(6) e^{i7\phi}$. A vector diagram representing a current distribution approximating this is given in Figure 5a. Figure 40 6b shows a ground plan of the applicable antenna arrangement with the horizontal field pattern at the ground level shown as a dotted line. There are 18 antennas numbered from 0 to 17. 45 In Figure 5a the vectors are numbered to correspond to the antennas to which they apply. It should be observed here that this type of array can be developed into a multiple ring array. The preferred way would be to plot the values of the 50 functions $J_5 e^{i5\phi}$ and $J_7 e^{i7\phi}$ combined and to place the antennas at the maxima and minima of the combined function, and to excite the antennas with currents varying in accordance with the applicable current distribution function. Another 55 way that would be wasteful of equipment would be to put rings of antennas as indicated by the maxima and minima of J_5 and rings as indicated by J_7 and exciting the J_5 rings with currents varying as $e^{i5\phi}$ and the J_7 rings with currents 60 varying as $e^{i7\phi}$. In either arrangement the currents would differ in phase by 180° in successive rings. Naturally the gain in directivity would be increased by increasing the number of rings.

65 As a final example of how to obtain a horizontal pattern likely to be useful in broadcast work we show one array that gives an intensity variation with azimuth that is proportional to

$$|1 + 1.27 \cos \phi|$$

70 We note that this corresponds to having more or less uniform intensity between $-\pi/2$ and $+\pi/2$ and nearly zero in the other half circle. Now the calculation goes much as before. We have

$$(1 + 1.27 \cos \phi) e^{in\phi} =$$

$$e^{in\phi} + (1.27/2) (e^{i(n+1)\phi} + e^{i(n-1)\phi})$$

Taking $n=6$, $k_p=6$ for definiteness, we find, in exactly the same way as before, that the current should be proportional to

$$e^{i6\phi} + \frac{1.27i J_6(4)}{2} e^{i7\phi} - \frac{1.27i J_6(4)}{2} e^{i5\phi}$$

5

A vector diagram for accomplishing this distribution is given in Figure 6a. The ground plan of the applicable array and the shape of the horizontal pattern of the radiation field at the surface of the ground (the dotted line) are shown in Figure 6b in which the small circles are numbered to correspond to the vectors of Figure 6a. Obviously this array could be expanded into a multiple ring array if desired.

10

It will be evident to those skilled in this art that our invention can be practiced in a variety of ways. It is not closely limited as to dimensions or radiation pattern. It is most conveniently calculated using the mathematical formulation we have described but practical results can be obtained by other methods. Having become aware of the general character of the antenna arrays practicable for the objects desired, one could compute them by the so-called cut and try methods of computation, or practical antennas could be found by a succession of comparative experiments with selected numbers of radiators and selected dimensions, currents and phase angles. Because of this we emphasize that our invention is novel in the results accomplished, the physical delineations, and in the methods of calculation. In our description of our invention we have shown the antennas arranged in circular rings. This is the preferred arrangement, but where a ring has only a few antennas the logical arrangement is with the antennas at the vertices of a regular polygon. For example, in some instances a ring could have as few as three antennas arranged in a triangle. It is generally desirable but not necessary for the antennas to be equally spaced on the circumference of the circle, or to be arranged in regular polygons. However when ground limitations or other practical considerations restrict the arrangement, considerable departures from symmetry and regular spacing are permissible.

15

The electrical connections of the antennas to the transmitter exciting them can be worked out on the basis of theory and practice already known in the art. Accordingly we do not deem it necessary to show wiring diagrams for our invention. The resemblance of the circuits used with our invention to circuits known in the art has been illustrated by a comparison of the polyphase ring of antennas with the rotating field structure of a polyphase armature. Considering the antennas as analogous to the coil sides in a polyphase motor, the phase of the currents in successive antennas around the ring, viewed at any instant, advances completing as many complete phase rotations as may be desired in one circumference of the ring. The current phasing in the antenna array can be accomplished by the use of transmission lines and tuned circuits of known types adapted to the particular requirements of the antenna concerned.

20

Having described our invention we claim:

25

1. A directional radiating system comprising at least two groups of approximately concentrically circularly disposed substantially vertical radiating elements and means for exciting the radiating elements of the respective groups with currents whose phases at any instant at successive places around the circles progress in phase

rotation at least one complete rotation in phase in one circumference of the circle, the numbers of complete phase rotations of the respective groups differing by at least one.

5. 2. A directional radiation system comprising an approximately circular ring of substantially vertical radiating elements and means for exciting said elements with currents which can be derived as the resultants of at least two polyphase currents whose phases at any instant at successive places around the circle progress in phase rotation at least one complete rotation in phase in one circumference of the circle, the numbers of phase rotations of the respective polyphase currents differing by at least one.

10. 3. A directional radiating system comprising a plurality of approximately concentric circular rings of substantially vertical radiating elements the radii of the circular rings being proportional to factors giving alternately maximum and minimum values of a current distribution series representing the currents required to produce the desired radiated field, the currents in the successive rings being of opposite phase, and means for exciting said elements.

15. 4. A directional radiating system comprising a plurality of approximately concentric circular rings of substantially vertical radiating elements the radii of the circular rings being proportional to factors giving alternately maximum and minimum values of a current distribution series representing the currents required to produce the desired radiated field, the currents in the successive rings being of opposite phase and having polyphase rotations around the circumferences of the rings of elements, and means for exciting said elements.

20. 5. A directional radiating system comprising a plurality of approximately concentric circular rings of substantially vertical radiating elements the radii of the circular rings being proportional to factors giving alternately maximum and minimum values of a current distribution series representing the currents required to produce the desired radiated field, the currents in the successive rings being of opposite phase and differing in phase from one element to the next in the respective rings of elements, and means for exciting said elements.

25. 6. A directional radiating system comprising a plurality of approximately concentric circular rings of substantially vertical radiating elements the radii of the circular rings being proportional to factors giving alternately maximum and minimum values of a current distribution series representing the currents required to produce the desired radiated field, the currents in the successive rings being of opposite phase and varying in magnitude around the rings as a function of the cosine of an azimuthal angle, and means for exciting said elements.

30. 7. A directional radiating system comprising a plurality of approximately concentric circular rings of substantially vertical radiating elements the radii of the rings being proportional to the values of the argument giving successive maxima and minima of a selected Bessel function, and means for exciting said elements with currents whose phases at any instant at successive places around the circles progress in phase rotation with a number of complete phase rotations in one circumference of the circle equal to the order of the selected Bessel function.

35. 8. A directional radiating system consisting of

a row of antennas spaced definite fractions of a wave length apart and means for exciting the antennas with currents which differ in phase between successive antennas by phase angles which are approximately 1.2 times 360° times the value 5 of said fraction of wave length spacing.

9. A directional radiating system consisting of a plurality of rows of antennas, the individual rows being on lines intersecting at specified geometrical angles, and means for exciting the antennas in the individual rows with currents differing in phase between adjacent antenna rows by electrical angles which are twice the corresponding geometrical angles between the rows.

10. A directional radiating system consisting 15 of a plurality of intersecting rows of antennas, the individual rows intersecting at specified geometrical angles, and means for exciting the antennas in the individual rows with currents differing in phase between adjacent antenna rows 20 by electrical angles which are substantially proportional to the corresponding geometrical angles between the rows.

11. A directional radiating system comprising 25 a plurality of antennas placed around the circumference of concentric rings, and means for exciting the antennas with currents which in each ring are 180° out of phase with the currents in the adjacent rings, and which in the elements of each ring differ in phase from one 30 element to the next.

12. A directional radiating system which consists of a plurality of antennas and means for exciting them with currents which vary from one antenna to the next, the distances between 35 adjacent antennas and the relative magnitudes of the currents in adjacent antennas being proportional respectively to arguments and magnitudes of the Bessel's functions corresponding to the frequency and field pattern of the radiation 40 of the system.

13. A directional radiating system comprising a plurality of radiating elements placed in concentric rings, and means for exciting the radiating elements with currents which differ in phase 45 from one radiating element to the next in each ring, the radii of the said rings being proportional to arguments, and the currents in the radiating elements of successive rings being proportional to the magnitudes of Bessel's functions 50 corresponding to the frequency and field pattern of the radiation of the system.

14. A directional radiating system comprising a plurality of vertical radiating elements materially less than one-half wave length high and 55 means for exciting the radiating elements with currents proportional to the magnitudes of Bessel's functions corresponding to the frequency and field pattern of the radiation of the system, and the distances between the radiating elements 60 being proportional to the arguments of said Bessel's functions.

15. A directional radiating system which consists of radiating elements, arranged in a circle of convenient radius, and means for causing currents to flow in the elements in such a way that the phases of the currents at successive radiating elements around the circle differ from one element to the next, the total of the phase angle differences in one circumference of the circle 70 being a multiple of 360° , said multiple being approximately 3 less than 2π times the ratio of the said radius of said circle to one wave length of the radiation of the system.

16. A radiating system consisting of a ring of 75

5 antennas, and means for exciting each antenna with a current presenting a phase displacement in reference to the currents in the adjacent antennas, the phase displacements between adjacent antennas, taken successively, adding to $2\pi n$ radians, n being at least equal to 3 less than 2π times the ratio of the radius of said ring of antennas to the wave length of the radiation of the system.

10 17. A radiating system consisting of a ring of antennas, and means for exciting each antenna with a current presenting a phase displacement in reference to the currents in the adjacent antennas, the phase displacements between adjacent antennas, taken successively, adding to $2\pi n$ radians, n being greater than 3 less than 2π times the ratio of the radius of said ring of antennas to the wave length of the radiation of the system.

15 18. A radiating system comprising a plurality of antennas arranged in concentric rings and means for exciting the antennas with currents such that the current distribution in the system approximates the current distribution specified by a Bessel's function of order n times the exponential of $in\phi$, where $i=\sqrt{-1}$ and ϕ is the azimuthal angle, and where the argument of the Bessel's function is k' times the radius, with k' greater than 2π divided by the wave length of the radiation.

20 19. A radiating system comprising a plurality of antennas arranged in concentric rings and means for exciting them with currents such that the current distribution in the system approximates the current distribution specified by a Bessel's function of order n times the exponential of $in\phi$, where $i=\sqrt{-1}$ and ϕ is the azimuthal angle, and where the argument of the Bessel's function is k' times the radius, where k' is determined by the condition that k' times the radius of the outermost ring of antennas shall exceed by approximately $1.8, 2\pi$ times that radius divided by the wave length of the radiation.

25 20. A radiating system comprising a plurality of antennas arranged in concentric rings and means for exciting the antennas with currents such that the current distribution in the system approximates the current distribution specified by a Bessel's function of order zero where the argument of the Bessel's function is k' times the radius, with k' greater than 2π divided by the wave length of the radiation.

30 21. A radiating system comprising a plurality of antennas arranged in concentric rings and means for exciting the antennas with currents such that the current distribution in the system approximates the current distribution specified by a Bessel's function of order zero where the argument of the Bessel's function is k' times the radius, and where k' is determined by the condition that k' times the radius of the outermost ring of antennas shall exceed by approximately $1.8, 2\pi$ times that radius divided by the wave length of the radiation.

35 22. A radiating system comprising a plurality of antennas arranged in concentric rings and

means for exciting the antennas, the antennas being so arranged and excited that the currents therein approximate the current distribution specified by a Bessel's function of order n times the exponential of $in\phi$ where $i=\sqrt{-1}$ and ϕ is the azimuthal angle where the argument of the Bessel's function is k' times the radius, with k' greater than $k=2\pi$ divided by the wave length of the radiation, k' being greater by an amount sufficient to make the radius of the outermost ring of antennas less by substantially one quarter wave length than the radius of the outermost ring of an hypothetical array similar in all respects except that the argument of the Bessel's function is taken as k times the radius.

40 23. A radiating system comprising a plurality of antennas arranged in concentric rings and means for exciting the antennas, the antennas being so arranged and excited that the currents therein approximate the current distribution specified by a Bessel's function of order zero and where the argument of the Bessel's function is k' times the radius, with k' greater than $k=2\pi$ divided by the wave length of the radiation, k' being greater by an amount sufficient to make the radius of the outermost ring of antennas less by substantially one quarter wave length than the radius of the outermost ring of an hypothetical array similar in all respects except that the argument of the Bessel's function is taken as k times the radius.

45 24. A radiating system comprising two concentric rings of antennas and an antenna at the center of said rings, and means for exciting the antennas with currents which are in phase in the several antennas in each respective ring, the current in the central antenna being in phase with the current in the outer ring, and the currents in the first ring being of opposite phase, the radii of the two rings being respectively approximately 0.480 and 0.878 of the wave length of the radiation.

50 25. A radiating system comprising three concentric rings of antennas and an antenna at the center of said rings, and means for exciting the antennas with currents which are in phase in the several antennas in each respective ring, and in which the currents in the central antenna and the second ring are in phase and of opposite phase to the currents in the first and third rings, the radii of the rings being respectively 0.517, 0.947, and 1.37 times the wave length of the radiation.

55 26. A radiating system comprising four concentric rings of antennas and an antenna at the center of said rings, and means for exciting the antennas with currents which are in phase in the several antennas in each respective ring, and in which the currents in the central antenna, and the second and fourth rings are in phase and of opposite phase to the currents in the first and third rings, the radii of the rings being respectively 0.536, 0.980, 1.42, and 1.82 times the wave length of the radiation.
